UNITED STATES PATENT OFFICE.

THOMAS T. ROCKETT, OF PHILADELPHIA, PENNSYLVANIA.

FURNACE-GRADE.

SPECIFICATION forming part of Letters Patent No. 436,194, dated September 9, 1890.

Application filed September 15, 1886. Serial No. 213,578. (No model.)

To all whom it may concern:

Be it known that I, THOMAS T. ROCKETT, a citizen of the United States, residing in Philadelphia, Pennsylvania, have invented certain 5 Improvements in Furnace-Grates, of which the following is a specification.

My invention consists in certain improvements in that class of shaking-grates in which the series of grate-bars are vibrated by one 10 handle, the objects of my invention being to simplify the construction of the operating parts and to permit each bar to be inserted or removed without disturbing the remaining bars.

15. In the accompanying drawings, Figure 1 is a plan view of a grate with my improvements. Fig. 2 is a section on the line 1 2, Fig. 1. Fig. 3 is a section on the line 3 4, Fig. 1. Fig. 4 is a detached perspective view of one of the 20 grate-bars. Fig. 5 is a detached view of a cover-plate forming part of the structure. Figs. 6, 7, 8, and 9 are diagrams illustrating the operation of the grate, and Fig. 10 is a detached view of a retaining-bar forming part 25 of the structure. Fig. 11 is a perspective view of a portion of the front plate broken away.

A represents part of the casing of the furnace, B the ash-pit, and D the fire-pot having the usual lining, E being the metal top plate 30 of the grate structure and F the grate-bars, which have their rear bearings in a segmental rib e of the plate E and have their front bearings in a bar G, (shown in Figs. 3 and 10,) said bar being hung to lugs g g' on the 35 plate E.

The bar G is pivoted to the lugs g, but is detachably secured to the lugs g' by a pin g², which passes through the front plate of the casing A, so that it can be easily manipulated 40 from the outside of the furnace.

Each grate-bar F has a spindle, on which is a lug f, bearing against the inner face of the bar G and serving to prevent the grate-bars from being removed or becoming loose 45 without first lowering the bar G.

The spindle of each grate-bar F has an arm a with right-angled lateral extension a', the several extensions being pivoted at i to a bar H, which thus serves to connect together all 50 of the arms a.

The pivot-pins i may be formed on the bar

H, as shown, or may be cast on the extensions of the arms a, as preferred.

I provide one of the grate-bars, preferably the end bar, with a handle I, the end bar being selected in order that the handle may be situated at one side of the furnace-door.

As shown in Fig. 6, the grate is at rest—that is to say, each grate-bar is flat and the handle I is in an upright position—but by 60 moving the handle I to the right and left, as shown in Figs. 7 and 8, the bars are rocked so as to shake the fuel and crush any cinders or clinkers that may pass between the bars.

By turning the handle I down to the position shown in Fig. 9 the arms a are depressed to a position in line with the handle and the grate-bars are caused to assume a vertical position, so as to dump the contents of the fire-pot.

The frame A has in front a series of recesses, a portion of each of which forms a bearing for a grate-bar spindle, other portions being enlarged, and these enlarged portions being under ordinary circumstances closed 75 by means of projections j on a cover-plate J on the inside of the front plate of the casing, this plate being held in place by means of studs m and keys n or other equivalent means, so that it can be readily released when necessary.

When it is desired to remove one of the grate-bars, the cover-plate J is removed and the pin g² withdrawn, so as to permit the bar G to drop. The arm a of the grate-bar to be 85 removed is then released from the control of the bar H and is turned to the position shown in Fig. 9, after which the grate-bar is moved laterally until it is in line with the adjacent recess in the front plate of the casing, and is 90 then removed longitudinally through said recess. After the grate-bar has been replaced the bar G is elevated and secured in the elevated position by the pin g² and the plate J is returned to its place and secured by the 95 keys or other fastening devices.

By this construction each grate-bar can be easily placed in or removed from position without disturbing the frame or any other portion of the grate, so that the repairing of 100 the grate does not involve the exercise of any special skill.

I claim as my invention—

1. The combination of the top plate, the grate, and grate-bars having front and rear journals integral with the body of the bar, 5 bearings in said plate for the rear journals, the front journals of the bars extending through orifices in the front plate of the furnace, and bearing-bar G, for the said front journals of the grate-bars, situated in the rear of the front 10 plate, and lugs on the under side of the top plate to which the bearing-bar G is detachably hinged, and with lugs on each of the journals of the grate-bars adapted to bear against the rear of the bar G, substantially 15 as and for the purpose set forth.
2. The combination of the top plate of the

grate and the bars having rear bearings in said plate, with a front bearing and retaining bar G, detachably secured to the under side of said top plate, the casing having recesses through which the grate-bars can be inserted and removed longitudinally, and a cover-plate for the said recesses, all substantially as specified.

In testimony whereof I have signed my 25 name to this specification in the presence of two subscribing witnesses.

THOS. T. ROCKETT.
